UNITED STATES PATENT OFFICE.

JOHN DU ROTH, OF UNIONTOWN, PENNSYLVANIA.

WHEEL.

SPECIFICATION forming part of Letters Patent No. 700,183, dated May 20, 1902.

Application filed August 3, 1900. Serial No. 25,783. (No model.)

To all whom it may concern:

Be it known that I, JOHN DU ROTH, a citizen of Germany, residing at Uniontown, in the county of Fayette and State of Pennsylvania, have invented or discovered new and useful Improvements in Wheels, of which the following is a specification.

In the accompanying drawings, which make part of this specification, Figure I is a section on the line I I of Fig. II, showing the oil-compartments. Fig. II is a section on the line II II of Fig. I. Fig. III is a detail view of the face of the wheel, showing the oil-cups. Fig. IV is a section on the line IV IV of Fig. III.

The purpose of my invention, generally stated, is to provide means for the economical distribution of oil from the oil-box to the axle of a wheel and to prevent the leakage of oil from the oil-filling hole of the oil-box and from the axle.

In the drawings, A represents the oil-box portion of the hub or the outer wall of the oil-box; B, the hub; C, the spokes of the wheel, and C' longitudinal partitions connecting the outer wall A and the hub B.

D represents contracted openings through the partitions C' at the hub B, and preferably centrally disposed thereof, providing means of communication for the oil between the several compartments E E' E² E³ E⁴ E⁵ of the oil-box formed by the partitions C', the outer wall A, the hub B, and the two end walls of the oil-box. Oil is introduced into either of the compartments E or E³, as may be desired or convenient, through the valve mechanisms F F. The valve mechanisms F F are each composed of a valve-seat G³, a ball-valve G², and a spring G' for holding the ball-valve normally against its seat. G is a packing-ring surrounding the axle H at the inner side of the wheel.

I is a spring-pin for holding the wheel in place on the axle.

K K are contracted openings in the bottoms of the compartments E E³ for feeding oil from said compartments to the axle.

Either or both of the compartments E E³ having been supplied with a sufficient quantity of oil by means of the valve mechanisms F F, the operation thereafter is as follows: By the motion of the wheel when first started the oil passes into the several compartments

of the oil-box, wherein by the action of centrifugal force throwing the larger portion of the oil toward the outer wall A of the box 55 it is retained. A sufficient quantity, however, flows down the sides of the partitions C' as may be above the plane of the axle. The quantity so flowing to the feed-holes K K will be small, but enough to meet the requirements. This arrangement insures a steady and continuous flow of oil toward the feed-holes K, while the bulk of the oil is held in reserve.

Another feature of my device is that by 65 reason of the location of the openings or ports D at the hub B, a majority of the compartments E E', &c., of the oil-box will hold their reserve of oil no matter in what position the wheel may come to rest, and when the wheel 70 begins to revolve there will be a more equal distribution of oil throughout the several compartments.

The construction of my device is practical not only in respect to its oiling capabilities, 75 but also as to the manufacture of the same, as I have overcome all difficulties in making the core, by which I can cast the wheel complete in one piece.

In casting my wheel I use a pattern with a 80 solid hub. When this pattern is removed from the sand, I place in the central hole made by the hub a chain or series of core-pieces for the compartments E to E⁵. This chain of cores is connected in series by bridging cores for the oil-passages D between the several compartments and is held up or suspended by means of wires in the usual manner. It will be understood, of course, that the pattern and cores are made in halves, 85 which when placed together form the complete mold, and that the usual vents are provided. After casting the sand is shaken and washed out through the passages D and the holes which are to receive the valve-plugs F F. 90

In the case of wheels having spokes the partitions C' preferably form continuations of the spokes, and thus strengthen the wheel.

I claim—

1. In a wheel, a hub, an oil-box surrounding the hub, longitudinal partitions in said oil-box dividing the same into a series of completely-closed compartments excepting that there are contracted oil passages or ports

formed in each of the partitions at the bases thereof which constitute the only means of communication between said compartments, the floor of one or more of the compartments 5 having a contracted opening for feeding oil to the axle, and means by which the oil-box may be supplied with oil; substantially as described.

2. In a wheel, a rim, a hub, an oil-box surrounding said hub, spokes connecting said oil-box and rim, the spokes extending through the oil-box and dividing the same into a series of completely-closed compartments excepting that there are contracted oil passages

or ports formed in each of the spoke extensions which constitute the only means of communication between said compartments, the floor of one or more of the compartments having a contracted opening for feeding oil to the axle, and means by which the oil-box 20 may be supplied with oil; substantially as described.

Signed at Uniontown this 30th day of July, 1900.

JOHN DU ROTH.
